INVENTOR

Charles B. Clark

United States Patent Office.

CHARLES B. CLARK, OF BUFFALO, NEW YORK.

Letters Patent No. 80,453, dated July 28, 1868.

IMPROVED BRUSH-HOLDER.

The Schedule referred to in these Letters Patent and making part of the same.

TO ALL WHOM IT MAY CONCERN:

Be it known that I, CHARLES B. CLARK, of the city of Buffalo, in the county of Erie, and State of New York, have invented a certain new and useful Improvement in Scrubbing-Brush Holders; and I do hereby declare that the following is a full and exact description thereof, reference being had to the accompanying drawings, making part of this specification, in which—

Figure 1 is a vertical section of the brush-holder, showing the position of the clamping-device.

Figure 2 is also a vertical plan, showing more fully the arrangement of the movable clamping-jaw and nut.

Figure 3 is a top view of the brush-holder.

Like letters refer to corresponding parts in all the figures.

My improvement relates to a clamping-device provided with a long handle, by which ordinary scrubbing-brushes can be held and operated by a person standing.

The invention consists in constructing a movable jaw connected with and operated by a thumb-nut working on an inclined hollow shank, as hereafter shown and described.

In the drawings, A represents a frame or casting, with a fixed jaw, C, and hollow inclined screw-shank, F, for inserting a wooden handle, D.

H is a movable jaw, working in a slot, as seen at L in fig. 2, said slot being cast through the screw-shank F.

E is a thumb-nut provided with a flange, G, and which engages in a slot or recess, K, of the movable jaw, and is operated by means of the thumb-pieces I, by which it is made to traverse the screw-shank in clamping or unclamping the brush.

The operation of my improvement is obvious. The brush is placed with its upper surface against the frame, so that the jaw C will contact with one side of the brush-stock, when the movable jaw H is pressed against the other side of the brush-stock, by rotating the thumb-nut E, which traverses the screw-shank F. The brush is readily released by turning the thumb-nut in the opposite direction.

The movable clamping-jaw is prevented from being displaced by the portion of the wooden handle which is driven into the screw-shank.

By the peculiar construction of this brush-holder I am enabled to dispense with drilling holes or using rivets, thereby greatly cheapening its manufacture. I also produce a very light article, combining strength and durability; and in efficiency and ease of operation it is excelled by none.

I do not claim a brush-stock or frame, in combination with a clamping-jaw, screw-shank, and thumb-nut, as I am aware that this has already been patented; but

What I claim as new, and desire to secure by Letters Patent, is—

Connecting the thumb-nut E with the movable jaw H, by means of the flange G and slot K, together with the mortise L in the screw-shank F, for the purpose specified.

In witness whereof, I have hereunto signed my name in the presence of two subscribing witnesses.

CHARLES B. CLARK.
